(57) **CLAIM**

The ornamental design for an electric fogger, as shown and described.

DESCRIPTION

FIG. 1 is a left perspective view of an electric fogger according to my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a top plan view thereof;

FIG. 8 is a right perspective view of thereof;

FIG. 9 is an enlarged view of the inset box illustrated in FIG. 1;

FIG. 10 is an enlarged view of the inset box illustrated in FIG. 2; and,

FIG. 11 is an enlarged view of the inset box illustrated in FIG. 8.

The broken lines shown in the drawings illustrate portions of the electric fogger that form no part of the claimed design. The numbers illustrated in FIGS. 4 and 6-11 are example numbers and form no part of the claimed design.

1 Claim, 11 Drawing Sheets
